UNITED STATES PATENT OFFICE.

CHARLES H. WATERS, OF GROTON, MASSACHUSETTS.

SPARK-ARRESTER.

SPECIFICATION forming part of Letters Patent No. 250,813, dated November 29, 1881.

Application filed April 25, 1881. (No model.)

To all whom it may concern:

Be it known that I, CHARLES H. WATERS, of Groton, in the county of Middlesex and State of Massachusetts, have invented certain 5 Improvements in Spark-Arresters, of which the following is a specification.

The present invention relates to the slotted basket or screen pipe cylinder employed in spark-arresters of the class described in United 10 States Letters Patent No. 223,427, dated January 6, 1880, to intercept and disintegrate the cinders before they are allowed to enter the smoke-stack.

The invention has for its object to provide 15 certain improvements in the construction of said slotted basket, when the same is made of parallel angular bars separated by spaces, which constitute the slots through which the cinders and sparks pass to the smoke-stack, said 20 improvements enabling the parts of the slotted basket to be expeditiously and conveniently arranged in operative position and held so that there can be no lateral springing or deflection of the bars to vary the width of the 25 slots between them.

To this end my invention consists in a slotted basket or screen pipe composed of parallel angular bars, arranged to present salient angles at the outer surface of the basket and at 30 the opposite side of the slots, as hereinafter described, secured together at their opposite ends and clamped at intermediate points between external and internal bands adapted to prevent lateral movement of the bars in any 35 direction, as I will now proceed to describe and claim, reference being had to the accompanying drawings, forming part of this specification, in which—

Figure 1 represents a horizontal section, on 40 line xx , Fig. 2, of a perforated cylinder or lift-pipe embodying my invention. Fig. 2 represents an elevation of a portion of the same. Fig. 3 represents a section on line yy , Fig. 2. Figs. 4 and 5 represent details, nearly full size. Fig. 6 represents a modification.

In all these figures similar letters refer to the same parts.

In the drawings, a represents a basket or screen pipe, adapted to be placed over the 50 exhaust-steam outlets within the smoke-arch of a locomotive, and to fit down closely to the

floor of the smoke-arch, as set forth in the before-named Letters Patent No. 223,427. The basket a extends, preferably, from the floor to the top of the smoke-arch, and said basket consists of vertical parallel metal bars b , angular in cross-section and preferably about one-fourth of an inch square, confined at bottom and top by suitable metallic collars or rings, d , into which the ends of the bars b are inserted. The 55 bars b are placed diagonally with the radius of the cylinder, (most clearly shown in Fig. 5,) and said bars are placed about eight-sixteenths of an inch from center to center, or so as to leave a clear space of about three-sixteenths 60 of an inch for the passage of smoke and cinders between the bars, although these distances may be varied, if found desirable in practice, without departing from the spirit of my invention.

It is important that the slits be of uniform width from end to end, so that no part of any slit will permit the passage of larger cinders or fragments than other parts.

The bars are confined and maintained at the 75 desired distance apart by metallic bands or hoops e , which are formed with shoulders f , inclined relatively to each other and adapted to coincide with the exterior faces, 22 , of the bars b , (see Fig. 5,) and to closely hug said 80 bars, and thus prevent any sidewise or rotary movement of the bars and maintain them in their relative positions at certain fixed distances apart. An internal metallic band, g , which may be plain, as shown, or shouldered, 85 like the bands e , bears upon the inner surface of the bars b near each band e , the bands e and g being suitably fastened together, preferably by bolts or rivets h , or otherwise secured.

In Fig. 4 a portion of the band e is shown 90 detached from the cylinder.

The fastening devices h pass through the slots between the bars b and securely bind the bands e and g upon the bars, so that the bars do not require to be riveted or attached to the 95 bands. It will be observed, therefore, that the bands can be very quickly applied, so that the operation of securing the bars against lateral movement at points between their ends is effected most expeditiously and effectively. The 100 shouldered bands are preferably made by casting, so that their shoulders are placed at uni-

form distances apart, and therefore insure uniformity in the width of the slots between the bars *b*.

In an organized spark-arrester the cylinder 5 *c* is surrounded by a flaring hood, &c., as shown in Letters Patent No. 223,427, above referred to, the general operation of the device being as therein set forth; but I do not confine myself to a flaring hood, as a straight cylinder 10 hood will answer the same purpose.

It will be observed that the angular bars *b*, arranged as shown, present salient angles 1 at their outer sides, which serve to split or disintegrate the cinders and sparks impinging 15 upon them, and converging sides, 2 2, (see Fig. 5,) which receive and guide the cinders and sparks to the spaces or slots 4 between the bars, and, in consequence of the obtuseness and uniformity of their inclination, do not enable the sparks and cinders to become wedged 20 between the bars. The bars *b* also present opposing sides 2 2 and 5 5, which form the sides of the openings 4, and apexes or angles 3 3, which assist in the reduction of sparks 25 and cinders entering said openings. The inner surfaces of the bars, when the latter are rectangular in cross-section, diverge abruptly from the openings 4, and furnish a free passage for the reduced sparks and cinders that pass 30 through said openings. I do not limit myself

to forming the inner surfaces of the bars as above described, however, as said surfaces may be flat, as shown in the modification, Fig. 6, the bars in this instance being triangular in cross-section.

If desired, the bars may be polygonal or rhomboidal in cross-section without departing from the spirit of my invention, so long as the arrangement is such as to afford the converging surfaces 2 2, extending from the outer portions of the bars to the slits 4 without variations of their inclination; and,

Having thus described my invention, I claim—

In a spark-arrester, the improved slotted 45 basket or screen pipe, composed of parallel vertical angular bars, arranged as shown, secured together at their opposite ends and clamped at intermediate points between external and internal bands, one or both of 50 which are shouldered to fit upon and afford lateral support to the bars, as set forth.

In testimony whereof I have signed my name to this specification, in the presence of two subscribing witnesses, this 23d day of April, A. 55 D. 1881.

CHARLES H. WATERS.
